Primary Examiner — Shawn T Gingrich

Assistant Examiner — Amanda Christensen

(57) **CLAIM**

The ornamental design for a magnetic wireless charging stand for tablet as shown and described.

DESCRIPTION

1. Magnetic wireless charging stand for tablet

1.1 : Perspective

1.2 : Front

1.3 : Back

1.4 : Left

1.5 : Right

1.6 : Top

1.7 : Bottom

1.8 : Perspective

The broken lines depict portions of the magnetic wireless charging stand for tablet that form no part of the claimed design. The cable is shown with a symbolic break in its length represented by a set of extended parallel broken lines. The appearance of any portion of the article between the extended parallel broken lines forms no part of the claimed design.

1 Claim, 8 Drawing Sheets
